(57) **CLAIM**

The ornamental design for a chair as shown and described.

DESCRIPTION

FIG. 1 is a perspective view of a chair showing my new design;

FIG. 2 is a front elevation view of the chair shown in FIG. 1;

FIG. 3 is a rear elevation view of the chair shown in FIG. 1; FIG. 4 is a side elevation view of the chair shown in FIG. 1, where the other side elevation view is a mirror image thereof;

FIG. 5 is a top plan view of the chair shown in FIG. 1; and, FIG. 6 is a bottom plan view of the chair shown in FIG. 1. The dashed broken lines on the drawing views of FIGS. 1-6 depict portions of the chair that form no part of the claimed design.

1 Claim, 6 Drawing Sheets
